(57) **CLAIM**

The ornamental design for a short-range wireless electronic lock, as shown and described.

DESCRIPTION

FIG. 1 is a top perspective view of the short-range wireless electronic lock, showing my new design;

FIG. 2 is a left side elevational view thereof, the right side elevational view being a mirror image;

FIG. 3 is a top elevational view thereof;

FIG. 4 is a bottom elevational view thereof; and,

FIG. 5 is a front elevational view.
